FIG. 2.

FIG. 3.

FIG. 5.

Inventor,

H. G. Roberts
By J. Edward Maybee
Atty.

UNITED STATES PATENT OFFICE.

HARRY G. ROBERTS, OF KITCHENER, ONTARIO, CANADA, ASSIGNOR TO THE WILLIAMS, GREENE & ROME COMPANY, LIMITED, OF KITCHENER, CANADA.

COLLAR.

1,306,278.

Specification of Letters Patent. Patented June 10, 1919.

Application filed November 7, 1918. Serial No. 261,519.

To all whom it may concern:

Be it known that I, HARRY G. ROBERTS, of the city of Kitchener, in the county of Waterloo, Province of Ontario, Canada, 5 have invented certain new and useful Improvements in Collars, of which the following is a specification.

This invention relates to soft collars comprising a band and a top turned down over 10 the band. In such collars it is usual to connect the ends of the top of the collar by a link or strap passing under the tie. Such connecting members have either been buttoned through the ends of the top or else 15 connected to the lining only. In the first construction the ends of the connecting member show at the outside of the ends of the top and the ends are more or less wrinkled or distorted. In the second construction 20 all the strain of the connecting member is taken by the lining, which is soon drawn out of shape. In either construction the points of attachment of the connecting member must be some distance back from 25 the edges of the ends of the top.

My object is to devise a collar in which the points of attachment of the connecting member will be entirely hidden, in which the strain of the connecting member will be 30 distributed over all the plies of fabric in the ends of the top in such a way as to avoid wrinkling and distortion of the ends, and in which the said points of connection of the connecting member will be as close 35 as possible to the edges of the top which adjoin so that the connecting member can be attached without folding back the collar ends too far, which has a tendency to crease them.

40 I attain my object by means of the construction hereinafter described and illustrated in the accompanying drawings in which—

Figure 1 is a plan view of a collar constructed in accordance with my invention and opened out flat;

45 Figs. 2, 3 and 4 are details illustrating the progressive steps in the construction of the collar; and

50 Fig. 5 a section through the end of the top of the collar exaggerated to better show the construction.

In the drawings like numerals of reference

indicate corresponding parts in the different figures.

55

1 is the band of the collar to which the top 2 is secured in the ordinary manner. The top is formed of a plurality of plies of material, preferably at least three, the facing 3, the lining 4 and the interlining 5. 60 These are laid together as shown in Fig. 2 and between them is sewed one end of the tape 6 at each side of the top of the collar. The top is then turned inside out as shown in Fig. 3, bringing the tape outside the collar. The tape is then folded back as shown in Fig. 4 and stitched down by the two lines of binding stitching which are used in finishing and stitching together the edges of the top of the collar. A loop 8 is thus 70 formed in the tape with which may be engaged any suitable attaching strap or connecting member, such as 9 shown in Fig. 1. This connecting member is hooked into the loops 8 from above, thereby precluding the 75 possibility of its accidentally falling out when in use. It will be understood that any form of attaching member, whether integral or formed in one or more separate parts, or whether inextensible or elastic, will 80 answer the purpose of my invention.

65

It will be understood that I use the term "tape" to include not only such material as is commonly known as tape and which may be either elastic or inelastic, but also to 85 include folded strips of cotton or other fabric, or heavy thread or cord, but ordinary commercial tape will usually be found to be the preferable material.

The collar top may also be formed by the 90 "machine turned and stitched" method, the hems being turned in on the pieces by machines so that the parts may be directly placed together as in Fig. 5 so that the top does not require to be turned inside out. 95 In this case the first line of binding stitching passes through the top and the tape, but is not visible on the tape, whereas the second or inner row passes through top and tape, and is visible on the tape.

100

From the construction described it will be seen that the strain of the connecting member does not fall on any loose portion of the collar, but is distributed among all the plies of material of which the top of 105 the collar is composed. The points of con-

nection are also entirely hidden, so that all the objects of my invention as set out in the preamble to this specification are satisfactorily attained.

5 What I claim as my invention is:—

1. A collar comprising a band and a top formed of a plurality of plies of material and provided with attaching means for a connecting member formed of tapes each

10 having one end sewn in one of the adjacent edges of the ends of the top between the plies thereof and its other end turned back to form a loop and secured to the top adjacent its first mentioned end by the binding stitching of the edges of the top.

15 2. A collar comprising a band and a top formed of a plurality of plies of material and provided with attaching means for a connecting member formed of tapes each secured to one of the adjacent edges of the ends of the top adjacent its first mentioned

20

end by the two spaced binding stitchings of the top, whereby the parts of each tape between the lines of stitching form loops.

3. A process of forming a collar top with 25 tape loop attachment at its end which consists in laying together two pieces of facing material and interlining and a piece of tape, stitching the collar top parts and the tape together, turning the band inside out with 30 the tape projecting and then folding back the tape against one face of the top and finally finishing the top with the usual binding stitching which is run through the tape to form a loop therein. 35

Signed at Kitchener this 30th day of October 1918.

HARRY G. ROBERTS.
